UNITED STATES PATENT OFFICE.

THOMAS COLE, OF ST. MARY'S, MISSOURI, ASSIGNOR OF TWO-THIRDS TO
JULES R. ROZIER AND EDWARD SCHAAF, OF SAME PLACE.

BOX-FASTENER.

SPECIFICATION forming part of Letters Patent No. 508,285, dated November 7, 1893.

Application filed April 28, 1893. Serial No. 472,153. (No model.)

To all whom it may concern:

Be it known that I, THOMAS COLE, of St. Mary's, in the county of Ste. Genevieve and State of Missouri, have invented a new and Improved Crate-Fastener, of which the following is a specification.

This invention relates generally to crates and boxes, and particularly to an improved lid fastening for said crate or box.

10 The objects of the invention are to provide a safe and simple fastening device which will permit crates being packed on top of each other and slid about without disturbing the fastening.

15 With these objects in view my invention consists in certain details of construction and combination of parts all of which will be fully described.

20 In the drawings forming a part of this specification—Figure 1 is a perspective view of my improvement and Fig. 2 is a detail vertical section of the same.

25 In practice I have applied my improvement to egg crates only but they are equally applicable to all classes of crates and transportation boxes and for the purpose of enabling others to make and use my invention I will describe the various parts in detail.

30 A indicates the box or crate which may be of any suitable construction, and divided into cells if desired. B indicates the lid, C the hinge and D the fastening.

35 The lid B may be an ordinary flat top but in practice I prefer to make it with the end pieces b which snugly fit the ends of the crate and keep the lid in its proper position both while open and closed. Horizontal cleats or strips a a are secured to the ends of the box A said strips being of the same width as the 40 end pieces b but they do not extend entirely to the rear edge of the box.

45 A metallic strap hinge C pivotally connects the strips a and end pieces b at each end of the crate, said straps being secured to the rear ends of the strips a and are connected to the end pieces b at a point a short distance to the

rear of the central lines. The lid is of course made somewhat larger than the crate proper, but if desired the lid can be made the same length as the crate and the strips a and end 50 pieces b dispensed with.

In order to secure the lid I provide the fastening hasps D which are essentially right angular in shape and pivotally connected at their lower ends to the spring staples D' driven into 55 the ends of the crate. Each of these staples has coiled spring side members the normal tendency of which is to hold the hasp tight upon the lid. An aperture d' is made in the hasp near its free end said aperture being 60 designed to receive a vertical stud or pin d² which is located in the center of a tapering recess d³ produced in the end of the lid. The hasp D is of rigid material and is so shaped that it must be pressed over the pin or stud d² until 65 the aperture d' receives the pin. The tension of the spring staples will then hold the hasp in place upon the pin and thus secure the lid. The ends of the lid are recessed as shown to permit the free ends of the hasps to rest thereon and permit one crate to be slid over another without disturbing the fastening. To unfasten the lid, the staples can be pressed up thus relieving the hasp of all pressure or the end 70 of the hasp may be raised by prying the end 75 above the pin.

Having thus described my invention, what I claim as new, and desire to secure by Letters Patent, is—

In a crate the box and its lid said lid having 80 recesses in its upper face and pins arranged in said recesses, the right angled hasps having apertures in their free ends and the staples to which the hasps are secured said staples having spring coils interposed between 85 their ends substantially as shown and described.

THOMAS COLE.
